COMBINATION SCOOP BOARD AND END GATE

Filed Sept. 13, 1921

Patented Oct. 9, 1923.

1,470,269

UNITED STATES PATENT OFFICE.

WILLIAM LAWRENCE, OF HAROURT, IOWA.

COMBINATION SCOOP BOARD AND END GATE.

Application filed September 13, 1921. Serial No. 500,393.

To all whom it may concern:

Be it known that I, WILLIAM LAWRENCE, a citizen of the United States, and resident of Harcourt, in the county of Webster and State of Iowa, have invented a certain new and useful Combination Scoop Board and End Gate, of which the following is a specification.

The object of my invention is to provide a simple, durable and inexpensive device for closing the ends of wagon boxes and similar containers, said device being adapted to be used as a shoveling board when in one position of its movement, and also being adapted to be moved to another position so that it may be used for a dump gate.

More specifically it is the object of my invention to provide a combination scoop board and end gate for wagon boxes provided with a single mechanism for moving the said scoop board to a number of positions so that the said board may be adapted to shovel grain out of the wagon bed, or to permit it to run out beneath the lower edges of said bed, and also for locking and securing the said scoop board in a closed position within the wagon bed.

A still further object is to provide in a device above referred to, detachable and adjustable means for preventing the upper edges of the side members of the box from spreading.

A still further object is to provide means for operating a combination scoop board and gate whereby the scoop board may be moved to a number of positions by the operation of a single mechanism to either place the scoop board in an inclined position for shoveling grain out of the wagon bed or to an elevated position to permit the grain to run out beneath the lower end of the scoop board, or to permit the scoop board to be easily and quickly detached from the wagon.

These and other objects will be apparent to those skilled in the art.

My invention consists in the construction, arrangement and combination of the various parts of the device, whereby the objects contemplated are attained, as more fully set forth, pointed out in my claims and illustrated in the accompanying drawings, in which:

Figure 1 is a perspective view of the rear end of a wagon bed showing the manner in which my improved device is applied.

Figure 2 is a side elevation of the same with the end gate in a position to be used as a scoop board.

Figure 3 is a detail plan view of one end of my improved mechanism as it is applied to one of the side members of the wagon box.

Figure 4 is a vertical sectional view taken on the line 4—4 of Figure 3.

Figure 5 is a perspective view of one of the detachable end gate supporting members.

The numeral 10 indicates the wagon box or similar container having side members 11 and a bottom 12, each of the side members 11 being provided with a side board 13, and each of the side boards 13 being provided with another side board 14.

Each of the said side boards and side members 11 of the box is provided with parallel cleats 15 spaced a slight distance apart and secured near the ends of the side boards and to their inner faces. These cleats are arranged vertically so that an end gate groove 16 is provided between them, and which is designed to receive the end gates of the ordinary construction.

Each of the side boards and side members of the box are provided with openings 17 which extend through the end cleat members 15 for the purpose of receiving end gate rods for preventing the side boards and side members of the box from spreading apart.

In boxes of this kind it is very difficult to remove the end gates for shoveling the grain into cribs, as the end gate rods must first be removed, after which the end gates are slid out of the grooves 16. When the said end gates are removed, a large amount of the grain will fall on the ground or floor. When it is desired to dump the contents of a wagon box, by elevating the front end, into an opening in the floor of a grain elevator or the like, it is impossible to remove the end gates without letting a large amount of the grain run on the floor.

To overcome these difficulties, I have provided a single end gate member to take the place of the ordinary end gates, which may be moved to a various number of positions to accomplish the desired results. The said device comprises supporting members 18, formed preferably of two strips of material 19 and 20 of lengths equal to the height of all of the said board members, the strips 19

- being of a thickness equal to the width of the grooves 16, and of a width equal to substantially two or three times the depth of said groove, each strip 19 being designed to have one of its edges enter the groove 16, while the strip 20 which is secured to its back face and adjacent to the inner faces of the cleats 15, as clearly shown in Figures 1 and 3.
- 10 The strip 20 is of such a width and so placed that a rabbet 21 is provided near the inner and back edges of the member 19. The strip 20 is provided with a number of bolts 21^a so arranged that they will pass through the end gate rod holes 17. A nut 22 is then placed on the bolts which will rigidly hold the strips 19 and 20 in position. These strips 19 and 20 are rigidly secured to each other.
- 15 20 The inner edge of the strip 19 near its lower end is provided with a vertical groove 23 of a depth substantially equal to the depth of the rabbet 21, and provided at its upper end with a notch 24 which communicates through the back face of the member 19, as clearly shown in Figure 5.
- 25 Mounted between the inner edges of the members 19, I have provided an end gate member 25 of a width equal substantially to the distance between the inner edges of the members 19, and provided with side members 26 secured to the inner face of its ends. This end gate member 25 and the side members 26 form what I shall term a scoop board. This scoop board is of a height slightly less than the height of the supports 18.
- 30 The back side of the end gate member 25 is provided with vertical strips 27 spaced a slight distance from the ends, which are for the purpose of rigidly securing the boards of the end gate member together.
- 35 The lower end of each of the members 26 is provided with a laterally extending pin 28 which is designed to extend in a corresponding groove 23, the said pins being so located that they will rest in the lower end of said grooves and the bottom edge of the end gate will rest against the floor 12.
- 40 45 50 Mounted on the upper end of each of the members 20, I have provided a bearing 29. These bearings 29 are designed to pivotally support an operating member that I shall term a bail 30. This bail is formed of a single rod having horizontal pivot members 31 mounted in the bearings 29.
- 55 60 65 Each of the members 31 is provided with downwardly extending portion 32, which is of a length substantially equal to the height of the end gate. The lower ends of the members 32 are connected by a transverse portion 33. The members 32 are designed to rest adjacent and parallel to the strips 20 when the door is in a closed position.
- 70 75 80 Secured near the upper end of the mem-

bers 27, I have provided bearing members 34 which are designed to pivotally support a horizontal rod 35. Each end of the rod 35 is provided with a loop 36 which is slidably mounted on an adjacent one of the members 32, as clearly shown in Figure 1.

A stop member 37 is secured to each of the members 32 a slight distance below the portion 31, to limit the upward movement of the said rod 35. The rods 32 are provided with detachable pins or keys 38 adjacent to the lower side of the loop 36.

The lower ends of the members 27 are beveled at 39 and the transverse member 33 is designed to rest when in its normal position against the said beveled faces. Pivoted buttons 40 are provided for securing the members 33 in position. Mounted in the upper ends of the members 19, I have provided eye bolts 41, each of which is provided with a chain 42, one of the chains being provided with a hook 43 and a slidable link 44, so that the free ends of the chains 42 may be secured to each other for the purpose of preventing the upper ends of the members 19 from spreading apart when grain is in the wagon box.

The operation of my device is as follows:

Figure 1 shows the end gate in its closed or normal position. Assuming that the wagon bed is loaded with grain such as corn, and it is desired to shovel the same from the bed, the link 44 is slid off of the end of the hook 43 and the inner ends of the chains 42 are separated from each other, the chains 42 being thrown over the top edge of the wagon and permitted to hang down on the outside. The buttons 40 are then turned so they will assume an upwardly extending position. This will release the member 33.

The keys 38 are then removed from the rods 32, then the member 33 is permitted to swing outwardly and upwardly and the upper end of the scoop board is permitted to swing outwardly and downwardly by the rod 35 sliding on the members 32.

This sliding movement is limited by means of the member 33. The lower end of the scoop board is swung about the pins 28 in the bottom of the grooves 23. The scoop board will assume the position shown in Figure 2, of the drawings, and when in said position serves as a shoveling board whereby the corn and similar grain may be shoveled from the bed. The member 33 serves to hold the outer end in its position.

If it is desired to dump the contents of the wagon bed into a grain elevator or similar device, the operator releases the buttons 40, as before described, without removing the pins 38. The member 33 is then swung outwardly and upwardly which will cause the upper end of the board 25 to swing outwardly and upwardly between the members 32. The lower end of the scoop board will

be elevated by permitting the pins 28 to side upwardly in the slots 23. The grain will then run out beneath the said scoop board. The amount of the opening between the lower end of the scoop board and the bottom of the wagon bed may be varied by raising and lowering the member 33, as in the position substantially shown in Figure 4. If it is desired, the member 33 may be forced downwardly and the flow of the grain shut off altogether.

This dumping process is usually accomplished by elevating the front of the wagon, which places the bottom 12 in an inclined position, and thereby permitting the grain to run out.

If it is desired to use the wagon box for hauling hogs or similar animals, the same scoop board may be used, as shown in Figure 1.

When it is desired to unload the hogs, it is desirable to remove the scoop board so that the hogs may be unloaded through the end of the wagon box. This may be easily and quickly accomplished by moving the member 33 to a slightly higher position than shown in Figure 4, which will cause the pins 28 to move in line with the notches 24, after which the lower end of the end gate may be moved rearwardly. This will permit the lower end of the scoop board to be free from the supports. The said lower end may then be rotated outwardly and upwardly about the members 31 as a pivot until the end gate assumes a horizontal position above the wagon bed, after which the hogs may then be unloaded through the end of the box and beneath the end gate 25.

The end gate may be removed entirely if so desired by springing the upper ends of the members 32 toward each other causing the members 31 to disengage the bearing members 29.

Thus it will be seen that I have provided a comparatively simple, durable and inexpensive end gate which is adapted to take the place of a shoveling board, and also adapted to be used in dumping grain in elevators, and when it is in a closed position it is rigidly held in place.

I claim as my invention:

1. In a device of the class described, spaced parallel and vertically arranged supports, a scoop board having its lower end pivotally and slidably mounted in and between the lower ends of said supports, a bail member pivotally mounted on the upper ends of the said supports having parallel and downwardly extending portions and a transverse portion connecting their lower ends, a horizontally arranged rod pivoted to the upper end of said scoop board and slidably mounted on the downwardly extending portions of said bail, the said portions being designed to rest substantially parallel

with the scoop board when the same is in an upright position, and a locking device for securing the transverse portion adjacent to said scoop board.

2. In a device of the class described, spaced parallel and vertically arranged supports, a scoop board having its lower end pivotally and slidably mounted in and between the lower ends of said supports, a bail member pivotally mounted on the upper ends of said supports having parallel and downwardly extending portions and a transverse portion connecting their lower ends, a horizontally arranged rod pivoted to the upper end of said scoop board and slidably mounted on the downwardly extending portions of said bail, means secured to the downwardly extending portions of said bail for limiting the movement of the horizontal rod in one direction, and detachable means for limiting the movement of said rod in the opposite direction, the said portions being designed to rest substantially parallel with the scoop board when the same is in an upright position, and a locking device for securing the transverse portion adjacent to the said scoop board.

3. In a device of the class described, spaced parallel and vertically arranged supports, a scoop board having its lower end pivotally and slidably mounted in and between the lower ends of said supports, a bail member pivotally mounted on the upper ends of said supports having parallel and downwardly extending portions and a transverse portion connecting their lower ends, a horizontally arranged rod pivoted to the upper end of said scoop board and slidably mounted on the downwardly extending portions of said bail, the said portions being designed to rest substantially parallel with the scoop board when the same is in an upright position, a locking device for securing the transverse portion adjacent to said scoop board, and means for detachably securing said supports within the end gate grooves of a wagon bed.

4. The combination of a wagon bed having a vertically arranged end gate groove in each of its side members near its end, a support mounted in each of said grooves, means for detachably securing said support in position, the lower end of the inner edge of each of said supports being provided with a vertical slot, a scoop board mounted between said supports having a lateral pivoted member near its lower end for each of said slots, a bail comprising parallel members having the lower ends connected by a transverse member, and each of its upper ends pivotally mounted to the upper end of one of the said supports, the distance between the parallel members of said bail being greater than the width of the scoop board, a horizontally arranged rod slidably

mounted on said parallel members, and means for pivotally mounting said rod adjacent to the upper edge of said scoop board, means for limiting the upward movement of said rod on the parallel members of said bail, and detachable means for limiting the downward movement of the horizontal rod on said bail, said bail being so arranged that as the transverse member is swung outwardly and upwardly, the upper end of said scoop board will be swung upwardly and outwardly and the lower end of said scoop board will be elevated vertically to form an opening between the bottom of the wagon box and the lower edge of said scoop board, said bail being also so arranged that when the detachable pins are removed from the parallel members, the horizontal rod will slide toward the transverse rod and permit the upper ends of the scoop board to swing outwardly and downwardly until the said horizontal rod is substantially adjacent to the transverse portion of said bail to permit the scoop board to be used for shoveling material out of the wagon box.

5. In combination, a wagon box, vertically arranged supports, a scoop board having its lower end pivotally and slidably mounted in and between said supports, a clutching means for supporting the upper end of said scoop board in a closed position when in one position of its movement, and for supporting the scoop board in an outwardly and upwardly inclined position when in another position of its movement with its lower end adjacent to the bottom of the wagon bed, and for supporting the lower end of said scoop board in an elevated position relative to the bottom of said wagon bed when in another position of its move- 40

ing its lower end pivotally and slidably mounted in and between said supports, a clutching means for supporting the upper 30 end of said scoop board in a closed position when in one position of its movement, and for supporting the scoop board in an outwardly and upwardly inclined position when in another position of its movement with 35 its lower end adjacent to the bottom of the wagon bed, and for supporting the lower end of said scoop board in an elevated position relative to the bottom of said wagon bed when in another position of its move- 40

6. In combination, a wagon bed, vertically arranged supports detachably connected thereto, a scoop board pivotally and slidably mounted between the lower ends of 45 said vertical supports, detachable and adjustable means for preventing the upper ends of said vertical supports from spreading apart, operative means for securing the scoop board in its closed position, or for moving the scoop board to position for a shoveling board, or to position for a dump gate.

WILLIAM LAWRENCE.
